US0D1044514S

(12) United States Design Patent (10) Patent No.: US D1,044,514 S
(45) Date of Patent: * Oct. 1, 2024

(54) POUCH WITH VENTS

(71) Applicant: Accedo Packaging, Inc, Sugar Land, TX (US)

(72) Inventor: David Gara Bertelsman, Sugar Land, TX (US)

(73) Assignee: ACCREDITO PACKAGING, INC, Sugar Land, TX (US)

() Term: 15 Years

(21) Appl. No.: 29/889,449

(22) Filed: Apr. 12, 2023

(51) LOC (14) Cl. 09-05

(52) U.S. Cl.

USPC D9/702

(58) Field of Classification Search

(57) CLAIM

The ornamental design for a pouch with vents, as shown and described.

DESCRIPTION

FIG. 1 is a front view of the pouch with vents showing my new design;

FIG. 2 is top view thereof;

FIG. 3 is a back view thereof;

FIG. 4 is a left side view thereof;

FIG. 5 is a right-side view thereof; and,

FIG. 6 is a bottom view thereof.

The broken line showing of line structure is included for the purpose of illustrating non-claimed subject matter and forms no part of the claimed design.

1 Claim, 3 Drawing Sheets
